LIQUID FLOW CONTROL UNIT

Barton R. Nelson, Portland, Oreg., assignor to Nelson Irrigation Corporation, Brimfield, Ill.

Filed Sept. 15, 1971, Ser. No. 180,940

Term of patent 14 years

Int. Cl. D23—01

U.S. Cl. D23—1

FIG. 1 is a plan view of the outlet end of a liquid flow control unit showing my new design;

FIG. 2 is an elevational view thereof; and

FIG. 3 is a plan view of the inlet end thereof.

I claim:

The ornamental design for a liquid flow control unit, as shown.
